J. J. SULLIVAN,
TROUSERS GREASER AND STRETCHER,
APPLICATION FILED JULY 21, 1917.

1,300,226.

Patented Apr. 8, 1919.

UNITED STATES PATENT OFFICE.

JOHN J. SULLIVAN, OF SPRINGFIELD, MASSACHUSETTS.

TROUSERS CREAMER AND STRETCHER.

1,300,226.

Specification of Letters Patent.

Patented Apr. 8, 1919.

Application filed July 21, 1917. Serial No. 181,954.

To all whom it may concern:

Be it known that I, JOHN J. SULLIVAN, a resident of Springfield, in the county of Hampden and State of Massachusetts, have 5 invented certain new and useful Improvements in Trouser Creasers and Stretchers, of which the following is a full, clear, and exact description.

This invention relates to improvements in 10 garment creasers and its leading object is to provide a simple device which will form a sharp crease in the trousers or garment along the entire leg of the trousers or garment.

15 Another object of the invention is the provision of a creaser formed of spring wire with a crease forming edge integral with the wire and formed thereon in the wire drawing operation, whereby the article may 20 be manufactured at low cost and easily assembled, and when assembled will present to the trousers leg a sharp edge which will, under tension, leave a sharp crease in the trousers leg.

25 Another object of the invention is the provision of a creaser and stretcher, consisting of a length of spring wire formed to provide opposing creaser members and spring legs between the creaser members, with a 30 tube for holding the confronting terminals of the wire secured together against displacement, and which tube is provided with an extension forming a tab adapted to receive advertising matter thereon.

35 With the above and other objects in view the invention consists of certain new and useful combinations, constructions and arrangements of parts, clearly described in the following specification and fully illustrated 40 in the accompanying drawings, in which:—

Figure 1 is a plan view of my improved creaser showing the spring legs between the creaser members retained in their contracted positions.

45 Fig. 2 is a side view of a clamp for gripping the edge of the garment over the creaser member to insure a positive sharp creasing of the trousers leg.

Fig. 3 is a transverse sectional view taken 50 on an enlarged scale, showing the creaser inserted in the leg of a pair of trousers and a pair of edge clamps applied to the opposing edges of the trousers leg to draw the garment of the trousers leg over the creaser member.

55 Fig. 4 is a detail sectional view through the retaining tube.

Fig. 5 is similar view showing a different position of the tube retained terminals of the wire frame of the creaser.

Fig. 6 is a cross sectional view showing the 60 relation of a single wire terminal to the retaining tube and tag thereof.

Fig. 7 is a detail view of a loop end provided with a spring coil.

Fig. 8 is a detail view of a plain loop end. 65

Referring to the accompanying drawings which illustrate the practical embodiment of the invention 5 designates the wire frame of my improved trousers creaser and stretcher, which is preferably formed of a single length 70 of wire and shaped to provide right and left or forward and rear creaser members 6 and 7.

The lower end of the creaser member 6 is curved slightly inward at 6^a and the lower end of the creaser member 7 is curved slightly 75 outward at 7^a, so as to properly shape the lower portion of the trousers leg.

The lower end portions of the creaser members 6 and 7 are connected to the spring legs or tension element 8, which consists of a V- 80 shaped body of wire having its end portions joined integrally to the end portions of the lower ends of the creaser members by the spring loops 9, whereby breaking of the connection will be avoided and the creaser members will be held outwardly under a proper 85 tension.

The forward or upper portions of the creaser members 6 and 7 are integrally connected by the spring loops 10 to the spring 90 leg 11, which is in the form of a V-shaped wire body. The terminals of the wire frame thus formed to provide the creaser members 6 and 7 and the tension legs therebetween, are brought together into confronting relation at the smaller end of the V of the tension element or leg 11 and bent toward each other, and then bent sharply at right angles to provide angular abutments or stops 12 and 13. 95

In order to retain the terminal portions of the wire frame in locked relation I arrange a tube 14 around the inbent portions and form a slot 14^a in this tube to receive the abutments or stops 12 and 13. This tube 14 is formed of flat sheet metal rolled upon it- 100 self around the terminals so as to lock the same in endwise relation to each other. The tube is formed on a strip of metal much longer than that required to provide the tube itself and this excess metal is extended to 105 provide a tab 15 designed to receive advertising matter or directions, and which is re-

tained in its original position by the interlocking of the stops 12 and 13 in the slot 14^a of the tube 14, and by the shape of the wire, which is non-circular, owing to the sharp edge 16 formed on the wire in the drawing thereof.

The spring or tension legs connecting the creaser members to each other are equipped with hooks 17 for holding said tension legs in contracted positions, as shown in Fig. 1. In using the device these hooks are first unhooked and then the lower end of the device is inserted in the larger end of the trousers leg.

15 The upper end portions of the creaser members 6 and 7 are directed outwardly so as to diverge from each other and correspond to the shape of the trousers leg. The inner portion of each tension leg or element is 20 formed with a spring loop portion 18 for increasing the tension exerted by the element on the creaser members, and to prevent breaking of the wire at the bend of said element.

The creaser members exert a pressure 25 against the inside of the trousers leg, and to insure rapid creasing of the trousers I provide auxiliary creaser clamps 19, which are in the form of long U-shaped clamping bars providing a wide flange 19^a and a narrower 30 flange or jaw 19^b, both of which have outwardly curved longitudinal edge portions 19^c, to permit of easy engagement with the trousers edge. The clamps 19 are provided with opposing handles 20, whereby the 35 clamps may be opened and closed, as will be readily understood.

Owing to the construction of the jaws of the clamps the fabric of the trousers leg will be drawn against the sharp edge of the

creaser member, so that a crease will be 40 formed in a shorter space of time and the crease will last longer when formed.

In Fig. 7 I show a terminal loop with a spring coil 21, and in Fig. 8 I show a terminal loop 22 of plain U-shaped construction. 45

Having described my invention I claim and desire to secure by Letters Patent:—

1. A garment creaser and stretcher consisting of a one-piece wire frame shaped to provide opposing creaser members having 50 sharp integral edges presented outwardly to engage the trousers leg and V-shaped tension elements integrally connected by open spring loops to said creaser members, the terminals of said frame being brought into confronting relation at the narrower end of one of said tension elements and formed with outwardly directed stops, and a tube having a slot to receive said stops embracing said confronting terminals to lock said terminals to 55 each other and having a portion extended laterally of the tube.

2. A combined trousers creaser and stretcher consisting of a wire frame providing opposing crease forming bars each of 60 said bars having V-shaped outer edges, inwardly projecting spring loops connecting said bars to each other and adapted to expand such bars against the leg of the pair of trousers and spring closed creaser clamps 65 adapted to hold the garment snugly against said V-shaped edge, each of said clamps being provided with a long side and a short side and with handles whereby the sides of said clamps can be expanded to permit of the 70 release from the garment.

Signed by me at Springfield.

JOHN J. SULLIVAN.
